To all whom it may concern:

Be it known that I, WALLACE MELVILLE Cox, a citizen of the United States, residing at New York, in the county of New York and State of New York, have invented and produced a new and original Design to be Worked into or upon Carpeting or Similar Fabrics; and I do hereby declare that the drawing accompanying this specification gives and conveys to any one skilled in the art of carpet-weaving a clear understanding of the same that is sufficient to enable such persons to use my invention.

The said drawing is a face view of the carpet embodying my design.

The design is in its relative aspect of ornamentation in rococo style, having large me-
